UNITED STATES PATENT OFFICE.

JOHN BJORK JOHNSON, OF EDMONTON, ALBERTA, CANADA.

LAUNDRY-CABINET.

1,277,599.

Specification of Letters Patent.

Patented Sept. 3, 1918.

Application filed March 29, 1918. Serial No. 225,494.

To all whom it may concern:

Be it known that I, JOHN BJORK JOHNSON, a subject of the King of Great Britain, and resident of the city of Edmonton, in the Province of Alberta and Dominion of Canada, have invented certain new and useful Improvements in Laundry-Cabinets, of which the following is a specification.

This invention relates to improvements in laundry cabinets, and the objects of the invention are to provide a combined ironing board and drying rack together with electrical connections for an iron, in such a manner that the drying rack and ironing board can be readily folded into the cabinet, thus occupying a minimum of space when not in commission, to provide means of suspending or attaching the cabinet to a wall so that the use of a table is not necessary when using the cabinet, and generally to adapt the several parts to better perform the functions required of them.

With the above and other objects in view, the invention consists essentially of the improved construction particularly described and set forth in the following specification and accompanying drawings forming part of the same.

In the drawings:

Fig. 1 is a perspective view of the improved cabinet with one of the side walls broken away, showing the drying rack and ironing board in open position ready for use.

Fig. 2 is a vertical section of the improved cabinet.

Fig. 3 is a transverse section of Fig. 2.

Like characters of reference refer to like parts in the several figures.

Referring to the drawings, A represents the improved cabinet which, in the embodiment illustrated, is substantially rectangular with the back 10 extending above the top wall and provided with an orifice 11 by means of which the cabinet may be suspended from a suitable hanging means on a wall.

This cabinet is divided into two compartments 12 and 13 by the transversely extending wall 14, the lower compartment 13 being lined with a heat resisting material and designed to hold an electric iron.

The front of the cabinet is closed by a hinged door 15, and the front edges of the side walls of the cabinet are notched as

shown at 16, while the edge of the door adjacent to the hinges is also notched as shown at 17.

In the upper compartment 12, a drying rack 18 is provided comprising a pair of spaced members 19 and 20 adapted to embrace and pivotally support a plurality of drying rods 21, the last said plate being embraced by a U-shaped bracket 22, the free ends of which are pivotally attached to a transversely extending rod 23 secured to the side walls of the cabinet.

This bracket 22 is connected at the front end to the side arms of a bail 24, the transverse arm of which is provided with an offset portion 25 with which the upper end of the rod 26 pivotally engages, the said rod being slidably supported in a bracket 27 mounted on the rear wall of the casing.

The lower end of the rod is offset as shown at 28 and passes between two angle brackets 29 which are arranged in alignment so that these angle brackets act as a further guide means and prevent any lateral displacement of the said rod.

In the lower end of the compartment 12, an ironing board 30 is pivotally supported and consists of two sections 31 and 32 connected by a hinge 33, the section 31 being pivotally attached to the transversely extending rod 34 secured to the lateral walls 35 of the casing.

The section 31 is also provided with an iron-stand 35 consisting of asbestos or other heat resisting material which is secured in position by a suitable framework of metal, and the two sections of the ironing board are covered with canvas or padded in any other suitable manner.

On the back wall of the casing, an electric socket 36 is provided to which the wires 37 are operatively attached and these wires may be designed to be engaged with an ordinary lighting socket in a house.

The back wall of the casing is also provided with a pair of spaced metallic strips 38 on which the transverse arm of the bail 24 rests so that any wear due to the rubbing of the said bail will not be detrimental to the cabinet, but will be taken up by the said strip.

When the cabinet is in use the door 15 is opened and the drying rack is rotated upwardly about the hinge pin 23 and when the

rods 21 are in a horizontal position, the side rods will, when rotated in a horizontal plane engage with the recesses 16 in the side wall of the cabinet and one of the said rods will 5 also engage with the recess 17 in the door 15.

The ironing board is now rotated about the hinge pin 34 and the inner end of the section 31 engages with and abuts the angle brackets 29 and also the offset end 28 of the 10 rod 26.

The section 32 is now rotated in a vertical plane until it lies in a horizontal position with the section 31 in which position it is supported.

15 The iron may now be attached to the socket 36 and when the wires 37 are connected to a light socket the operation of ironing may be commenced.

As the several articles are ironed they may 20 be hung over the drying rods 14 to air. When the ironing board is in a horizontal position, the rack 18 is maintained also in a horizontal position even although the side rods become disengaged from the slots 16.

25 After the ironing has been completed, the iron is disconnected and placed in the compartment 13 and the section 32 of the ironing board folded on top of the section 31, whereupon the drying rods 21 of the rack 30 18 are rotated so that their points are in close proximity to each other, thus freeing the side rods from the recesses 16 and 17 in the wall of the cabinet and the door.

On the ironing board being rotated about 35 the rod 34, the rack 18 will immediately rotate about the rod 23 and so become located entirely within the cabinet in front of the folded ironing board.

From this description it will be seen that 40 I have invented a cabinet which can be advantageously utilized in households, apartments and like places and in which the several parts of the device can be quickly arranged for use, while, when the cabinet is 45 not in commission the several parts can be stored therein and so make a compact arrangement which will not occupy too much valuable space.

As many changes could be made in the 50 above construction and many apparently widely different embodiments of my invention within the scope of the claims, constructed without departing from the spirit or scope thereof, it is intended that all matter contained in the accompanying specifica- 55

tion and drawings shall be interpreted as illustrative and not in a limiting sense.

What I claim as my invention is:

1. A laundry cabinet of the class described, comprising a casing, a collapsible ironing board in the casing, and a drying rack above the casing, and means controlled by the said ironing board when open to maintain the drying rack in open position. 60

2. A laundry cabinet of the class described, comprising a casing, a collapsible ironing board pivotally supported in the casing, a drying rack pivotally supported in the casing to fold downwardly, and means carried by the drying rack adapted to be engaged 65 with the ironing board when opened to hold the rack in raised position.

3. A laundry cabinet of the class described, comprising a casing, a collapsible ironing board pivotally supported in the casing, a 70 bracket carried by the casing adapted to engage the inner end of the ironing board when open, a collapsible drying rack pivotally supported to fold downwardly in the casing, and controlling means for the drying rack adapted to engage with the ironing board when open. 75

4. A laundry cabinet of the class described, comprising a casing closed with a hinged door, the edges of the lateral walls of the 80 casing having recesses therein, a collapsible ironing board pivotally mounted in the casing and a drying rack pivotally mounted in the casing having side members adapted to engage with the said recesses and supporting means additional to said recesses controlled by the movement of the ironing board. 85

5. A laundry cabinet of the class described, comprising a casing, a collapsible ironing 90 board pivotally mounted in the casing, a collapsible drying rack pivotally mounted in the casing, a bail carried by the drying rack and a rod connected with the bail having an offset end designed to engage with the ironing board when open whereby the movement of the ironing board to open position moves the drying rack to open position. 95

In witness whereof I have hereunto set my hand in the presence of two witnesses. 100

JOHN BJORK JOHNSON.

Witnesses:

CHRIS. B. JOHNSON,
D. HOPLEY.
